Primary Examiner — John Windmuller*Assistant Examiner* — Steven J Czyz(74) Attorney, Agent, or Firm — Brian P. McCloskey; Elizabeth Morters(57) CLAIM

The ornamental design for a container for personal care, as shown and described.

DESCRIPTION

FIG. 1 is a perspective view of a container for personal care; FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the container illustrated in broken lines form no part of the claimed design.

1 Claim, 4 Drawing Sheets(56)
